UNITED STATES PATENT OFFICE

155,366

DESIGN FOR A DISPLAY TABLE FOR YARD GOODS

W. L. Stensgaard, Park Ridge, Ill., assignor to
Goodall-Sanford, Inc., a corporation of Maine

Application January 6, 1948, Serial No. 143,565

Term of patent 14 years

(Cl. D80—9)

To all whom it may concern:

Be it known that I, W. L. Stensgaard, a citizen of the United States, residing at Park Ridge, in the county of Cook and State of Illinois, have invented a new, original, and ornamental Design for a Display Table for Yard Goods, of which the following is a specification, reference being had to the accompanying drawing, forming part thereof.

Figure 1 is a side elevational view of a display table for yard goods embodying my design;

Figure 2 is a top plan view of the device of Figure 1; and

Figure 3 is an end elevational view of the same device.

I claim:
The ornamental design for a display table for yard goods, as shown.

W. L. STENSGAARD.
